UNITED STATES PATENT OFFICE

170,460

COMBINATION ICE CHOPPER AND SCRAPER FOR WINDSHIELDS AND THE LIKE

Alfred K. Hauser, Chicago, Ill.

Application January 30, 1952, Serial No. 18,305

Term of patent 14 years

(Cl. D9--6)

To all whom it may concern:

Be it known that Alfred K. Hauser, a citizen of the United States, residing at Chicago, in the county of Cook and State of Illinois, have invented a new, original, and ornamental Design for a Combination Ice Chopper and Scraper for Windshields and the like, of which the following is a specification, reference being had to the accompanying drawing, forming a part thereof.

In the drawing:

Fig. 1 is a top plan view of a combination ice chopper and scraper for windshields and the like, showing my new design.

Fig. 2 is a side elevation of the design of Fig. 1;

Fig. 3 is a view in cross-section taken along the center line of the design of Fig. 1; and

Fig. 4 is a front elevational view thereof.

I claim:

The ornamental design for a combination ice chopper and scraper for windshields and the like, as shown.

ALFRED K. HAUSER.
